SELF-EXPANDING MANDREL FOR PILE CASINGS

John S. McKee, Palatine, Ill.

Application November 5, 1956, Serial No. 620,224

12 Claims. (Cl. 61—79)

For various types of construction it is desirable to have piles extending down into the earth to provide sufficiently dependable support for the structure to be built. One preferred form of pile comprises a relatively thin steel shell filled with concrete. Both for economy and for best results, it is preferred that these steel shells be driven into the ground. This has been accomplished for some years by placing in the steel shell an expanding mandrel which made possible the driving of the relatively weak steel shell into the ground by operation of a pile driver on the top of the combined assembly of shell and mandrel.

According to the present invention, a greatly simplified expanding mandrel for this purpose is provided. The simplification is achieved chiefly by making the mandrel self-expanding in the sense that the main longitudinal stringers of the mandrel which must be thrust apart for gripping the inside of the pile casing or shell, are also the main operating members by which the expansion is produced. Heretofore, the expansion has involved some sort of a core which thrusts apart the main segments or longitudinal stringers, but such core is not required by the present invention.

According to the present invention, the mandrel includes four sturdy longitudinally extending segments much as before. When they are inserted into the pile shell, only two of the four rest on the bottom of the shell initially. They may be called passive segments. The other two, called active segments, are somewhat raised in position. Between the passive segments and the active segments, wedges are provided, so that as the active segments are driven down to a seated position, all four segments are wedged apart to press themselves firmly against the inside surfaces of the pile shell, forming a firm driving unit.

To remove the mandrel the two active segments are initially raised thereby releasing the wedges from one another so that the mandrel may collapse by having its four segments draw together. The collapsing action may be ensured by means for positively drawing the segments toward one another as the first two segments are raised. This may be accomplished by camming means secured to the respective segments, in which event the same means may serve the function of maintaining the four stringers approximately equally spaced at all times.

It is not necessary that the segments be unitary for the full length of the pile shell. Mandrel units including four segments each may be made up in convenient lengths and it is quite easy to combine them into a chain. After one unit has been moved into a shell, and perhaps after it is driven, its two active segments may be secured to the two active segments of another unit so that the two units would then function as one mandrel. There may be some differences between the successive units. The first unit will normally be provided at its entering end with a base plate carried by the two passive segments, and against which all four segments will bear after the active segments have been driven home, and during the

2

pile driving operation. A driving head suitable for direct co-operation with the pile driver, and also provided with means for withdrawing the mandrel, will be provided at the top of the mandrel, whether of one or more units.

Additional objects and advantages of the invention will be apparent from the following description and from the drawings.

Designation of figures

10 Fig. 1 is a somewhat diagrammatic view showing an expanded mandrel in a shell being driven into the ground.

Figs. 2 and 3 are upper and lower portions of the expanded mandrel unit in Fig. 1, with portions broken away.

Figs. 4 and 5 are horizontal sectional views taken approximately at 4—4 and 5—5 of Fig. 2.

Fig. 6 is a top view of one of the mandrel segments.

Fig. 7 is a horizontal sectional view of one of the mandrel segments, being taken through a hand hole.

Fig. 8 is a view showing the relationship of the expanded mandrel, the driving head and the lifting ring.

Fig. 9 is an exploded view showing the upper portions of three of the four segments, the face plates being partly omitted.

Fig. 10 is a somewhat diagrammatic view partly in vertical cross-section, and with portions omitted, showing a multi-unit mandrel with the active segments of the upper units connected to the driving head, so that the entire mandrel can be lifted by the lifting ring.

Fig. 11 is a similar view showing the parts after the upper mandrel has been expanded and the shells welded together.

Intent clause

35 Although the law requires a full and exact description of at least one form of the invention, such as that which follows, it is, of course, the purpose of a patent to cover each new inventive concept therein no matter how it may later be disguised by variations in form or additions of further improvements; and the appended claims are intended to accomplish this purpose by particularly pointing out the parts, improvements, or combinations in which the inventive concepts are found.

General description

Driving of the shell 11 is accomplished with the aid of a mandrel 12 which firmly engages the shell 11 and with it forms one sturdy unit for driving. During driving, a driving head 13 is positioned on the top of the mandrel 12. When the shell 11 has been driven into the desired depth or until its top is approximately flush with the ground, the ring 14 may be raised thus collapsing the mandrel and withdrawing it from the shell. The shell will then be filled with concrete to provide a cast-in-place concrete pile. The present invention is concerned especially with the construction of the expanding mandrel 12.

The mandrel is made up of four segments 16, two of which may be more specifically designated as 16A and the other two as 16P. The two segments 16A may be called active segments and the two segments 16P may be called passive segments. During expansion and collapsing, the active segments move up and down relative to the passive segments. As seen perhaps best in Fig. 2, wedges 17A are provided on the active segments 16A, and co-operating wedges 17P are provided on the passive segments 16P. As the active segments are driven down from a position above that shown in Fig. 2, the interaction of the wedges 17A and 17P spreads the segments apart. Fig. 2 shows only one set of wedges, but as will be seen from Fig. 9, each active segment 16A

has wedge means 17A on one face for engaging one of the segments 16P and another wedge means 17A on its other face for engaging the other of the passive segments 16P. The other of the active segments likewise has wedges engaging wedges on both of the passive segments. The various sets of wedges are located at a sufficient number of points along the length of the segments so that the segments will not flex unduly between wedges, and will engage the shell along its full length.

When the active segments are drawn upwardly so that the wedges no longer hold the segments spread apart, the segments may be drawn together in a suitable manner. Although springs may be sufficient, the present preference is for providing cam plates 18 on the active segments riding in slots 19 on the passive segments. One reason these cam plates are preferred at present is that they also serve the additional purposes of raising the passive segments after sufficient lost motion to permit collapsing, and maintaining proper alignment or relative disposition of the four segments as they expand and contract, keeping them equally spaced. Without some such guide, the two active segments might move closer together or further apart than the spacing of the passive segments and possibly distort the shell to an oval cross-section. Alignment guides which do not serve as collapsing cams could be used for this latter function, and other limits of relative movement could be used.

Structure of segments

Each segment may desirably comprise mainly a steel angle bar 21 extending its full length and a shell face plate 22 also extending the full length. Although these may be welded together along their full length, that does not appear to be necessary. They should be welded together at frequent intervals, however. Before they are welded together, a series of gusset plates 23 may be welded within the angle bars, serving both to reinforce the angle bars and to provide a support for the central portion of the face plate 22. At the present time, however, it is believed that these need only be provided in the vicinity of the wedges, where they will serve the additional purpose of transmitting the wedging thrust to the face plate 22 and safeguarding against distortion of the angle bars 21 by the wedging pressure. The segments could also be cast.

Wherever necessary for access in assembly or for purposes described below, hand holes 26 may be provided as shown in Fig. 8. Cover plates may be fitted in these holes to rest against suitable internal flanges, if conditions are such that the shell may otherwise be pressed into the holes.

At the upper ends of the two active segments 16A, holes may be provided for the passage of pin 27. The hole 28 in the face plate 22 may be relatively large, but the hole 29 through the angle bar 21 preferably fits the pin 27 more closely, for load bearing purposes. As a matter of fact, it is desirable to reinforce the angle bar 21 in the vicinity of each of the holes 29, as by welding plates 31 to them, and perhaps plates 32 on the inside. Such reinforcing at the upper and lower ends of all of the angle bars 21 may be desirable, to help transmit the pile driver blows.

The slots 19 may be formed by welding two short spacer plates 33 to one face of the angle bar 21 and welding a longer plate 34 to the two spacer plates and bridging between them as shown in Fig. 9.

Although Figs. 4 and 5 and some other figures indicate numerous bolts for holding the parts together, it is generally preferred that welding be used. Adjustment of wedges originally, or after wear, may be done by insertion of shims (if not welded), resurfacing the wearing faces or addition of new wearing surfaces. Sometimes it can be done by adding shim plates to the top of the active segments 16A and to the bottom of passive segments 16P.

Base plate

Before driving the shell 11, it will be provided with a boot 36 secured and sealed to the shell, as by welding. To safeguard against punching through this boot 36, and to ensure distributed bearing thereon, the bottom of the mandrel is provided with a base plate 37 as seen in Fig. 3. It is necessary that this base plate be carried in a manner which does not interfere with the expanding and contracting action of the segments. To this end, the base plate may be secured in a manner illustrated in Fig. 3. A bolt 38 may extend through the base plate to a gusset plate 39 substantially above the base plate. The end plate 41 of the segment 16P is slotted to permit the segment 16P to move inwardly and outwardly with respect to the bolt 38 and the base plate 37. Any gusset plates 43 between the gusset plate 39 and the end plate 41 are similarly slotted. Only two bolts 38 are provided, one extending into and being secured to each of the passive segments 16P. Thus the active segments 16A are left free to move vertically. The top of each segment is also provided with an end plate 41.

Driving head

The driving head 13 may be in the form shown in Fig. 8. The upper portion is shaped for conventionally engaging the pile driver, and the lower portion is adapted to surround the mandrel and bear against its upper end. Pin 27 extends through its skirt and thus holds the mandrel, or at least the two active segments 16A within the skirt. After the two active segments have been driven to the same level as the two passive segments, the body of the driving head 13 will rest on all four segments. At present it is preferred that the entire assembly be supported and held in proper relationship with the pile driver mechanism, represented diagrammatically at 45, Fig. 11, by a lifting ring 14 which may be provided with suitable ears 47 to which a cable may be secured for binding the ring 14 to the pile driver structure. It will be observed that the head 13 can rotate within the ring 14, and therefore a spirally corrugated shell is free to screw itself into the ground as it is driven.

Cleats

For use with spirally corrugated shells, spiral cleats 49 as seen in Figs. 4 and 8 may be secured at suitable intervals on the passive segments 16P to fit into the spiral internal grooves as these two segments are spread apart. Similarly, horizontal cleats may be used with horizontally corrugated shells and hard-faced welding beads or sharp gripping surfaces may be applied to the mandrel segments when necessary with smooth shells. For some conditions cleats or gripping surfaces may also be desirable on the active segments 16A, although the care required in spacing and forming them to clear the internal ribs in the shells as the segments move up or down for collapsing or expanding the mandrel, indicates omitting these unless found necessary.

Chain of mandrel units

When it is desired to drive a pile deeper than the length of one mandrel unit, this can be accomplished by providing a chain of mandrel units as seen in Fig. 10. A connecting link 51 is used for connecting the active segments of the two units. Thus a pin 52 extends through the link 51 and into the active segments 16A of the upper units of the chain of mandrel units, and a second pin 52 extends through the link 51 and into the segments 16A of the lower unit. Preferably the lower of these pins 52 extends through a lost motion slot 54 in the link which is long enough for the following operation:

After one shell 11 has been driven into the ground until it is nearly flush therewith, the pin 27 of Fig. 8 can be withdrawn and the driving head 13 and ring 14 can be lifted away and secured to another mandrel unit. After this mandrel unit has been threaded into a second

shell and the latter held thereon temporarily in a suitable manner (as by rope 55), this shell and mandrel can be lowered to the position shown in Fig. 10 with the two passive segments of the upper unit resting on the passive segments of the lower unit. The link 51 will have been secured to the upper unit by upper pin 52 before the upper unit is quite lowered to this position. At this time the lower pin 52 can be slipped in place. The ring 14 may now be raised to draw the lower active segments 16A upwardly enough to allow at least partial collapsing of the lower mandrel unit. Thereupon the upper shell may be loosened and lowered to slide over the lower mandrel unit until it is in contact with the lower shell 11. The two sections of shell may then be joined together, and sealed if necessary, in a suitable manner, as by welding, screwing together or applying a sleeve or sleeves welded or otherwise sealed to them. Now the upper mandrel unit may be lowered until the passive segments of it again rest on the passive segments of the lower mandrel unit. At this time, the link 51 will probably drop to a point where it is no longer supporting the pin 52. As the upper active segments 16A are driven downwardly, they will come into engagement with the lower active segments 16A and drive them downwardly also. When the lower active segments 16A have thus been driven down to the level of the passive segments, the upper active segments 16A will also be driven to the level of the upper passive segments, and both mandrel units will be properly expanded to permit further driving of the now combined shell until it has been driven enough further for the upper shell also to be at ground level. If greater depth is required, the same process may be repeated with a third mandrel unit, and a third shell.

The pins 52 may be kept centered, or retained within the mandrels in any suitable manner, as by a spring latch engaging them, or a draw bolt blocking their removal.

In some instances, it may be preferred to make a two unit mandrel without the lost motion provided by slot 54. Either the active segments may be coupled snugly by a link such as 54, but shorter, or each of the active (or each of all four) upper segments can be rigidly secured to the corresponding lower segment. For this purpose, holes 56 may be provided in all end plates 41, so they may easily be bolted together. Where the hole is elongated to permit movement of bolt 38, the securing bolt may be of corresponding cross-section.

If a pile is desired that is larger in its upper portions than below, this can be accomplished by driving the smaller shell first with a mandrel fitting it, and then using a larger shell and mandrel. A suitable adapter may be used for coupling the two mandrels and transmitting the thrust of the upper to the lower. A suitable coupling or adapter is also used to join the lower, small section to the larger, upper section of the shell. Also, as in present practice, heavy wall pipe may be driven first, and a mandrel-filled core applied to the top thereof for further driving.

The "chain of units" feature is most advantageous when the self-expanding mandrel of this invention is used, but would be of utility also if a separate stringer in the form of a wedging core were used. In that event the cores would be the active stringers and would be linked as described above with respect to the active stringers heretofore called segments. The remaining or passive stringers or segments would be treated as described for the passive segments above.

I claim:

1. An expanding mandrel unit for driving pile casings including four sturdy longitudinal segments each adapted to transmit driving load, and to back up the casing, arranged in a group with a face of each exposed peripherally, with wedge means secured to each segment and engaging the companion wedge means on the adjacent segments, the wedges on an active opposite pair of said segments facing downwardly and the wedges on the second

opposite pair of segments facing upwardly, and the wedges being so positioned that as the active segments are driven down with respect to the passive segments to the same level, the mandrel unit will be expanded with the wedges in engagement, the active pair of segments being shiftable upwardly from the level of the other segments and as they are so shifted, the mandrel unit being collapsible to lie within a smaller diameter than that which it occupies when expanded.

2. An expanding mandrel unit according to claim 1, including a base plate carried entirely by the second pair of segments, with freedom of the second pair of segments to shift inwardly and outwardly, and freedom of the active segments to shift upwardly and downwardly.

3. An expanding mandrel comprising two units one above the other, each a mandrel as defined in claim 1, with the active segments of one unit secured to the active segments of the other unit.

4. An expanding mandrel in accordance with claim 3, in which the segments secured together are secured with a lost motion connection allowing the upper unit to rest with all of its segments on the segments of the lower unit and alternatively to be collapsed without collapsing the lower unit.

5. An expanding mandrel unit in accordance with claim 1, including cam means co-operating between the active segments and the other segments to collapse the mandrel as the active segments are raised.

6. An expanding mandrel unit in accordance with claim 1, including cam means co-operating between the active segments and the other segments to collapse the mandrel as the active segments are raised and to maintain alignment of the segments.

7. An expanding mandrel unit in accordance with claim 1, including cam means co-operating between the active segments and the other segments to collapse the mandrel as the active segments are raised and to raise the other segments as upward movement of the active segments is continued beyond the amount required for collapsing.

8. An expanding mandrel unit in accordance with claim 1, including means to maintain alignment of the segments.

9. An expanding mandrel unit in accordance with claim 1, including means to raise the other segments as upward movements of the active segments is continued beyond the amount required for collapsing.

10. An expanding mandrel unit for driving pile casings including a plurality of sturdy longitudinal segments each adapted to transmit driving load, and to back up the casing, arranged in a group with a face of each exposed peripherally, with wedge means secured to each segment and engaging the companion wedge means on an adjacent segment, the wedges on at least one active segment of said segments facing downwardly and the wedges on the segment adjacent to the active segment or segments facing upwardly, and the wedges being so positioned that as the active segments are driven down with respect to the passive segments to the same level, the mandrel unit will be expanded with the wedges in engagement, the active segment being shiftable upwardly from the level of the other segments and as they are so shifted, the mandrel unit being collapsible to lie within a smaller cross-section than that which it occupies when expanded.

11. A chain of expanding mandrel units, each having a plurality of passive stringers and an active stringer movable longitudinally between them and having an exposed head for being driven, and having a fitting for being raised by a cable, said stringers having spreading means associated with them for spreading the passive stringers apart when the active stringer is driven downwardly and for allowing them to move toward one another to collapse the unit when the active stringer is raised; means separately linking the active stringers together and when connecting them providing lost motion so that the upper stringer can be raised to collapse its unit, raised further

to raise the lower active stringer to collapse the lower unit, and driven down with the upper passive stringers resting on the lower passive stringers, to expand both units; and means to raise the passive stringers by support from the active stringers after the units have collapsed.

12. A chain of expanding mandrel units, each having a plurality of passive stringers and an active stringer movable longitudinally between them and having an exposed head for being driven, and having a fitting for being raised by a cable, said stringers having spreading means associated with them for spreading the passive stringers apart when the active stringer is driven downwardly and for allowing them to move toward one another to collapse the unit when the active stringer is raised; means linking the active stringers together and when connecting them providing lost motion so that the upper stringer can be raised to collapse its unit, raised

further to raise the lower active stringer to collapse the lower unit, and driven down, with the upper passive stringers resting on the lower passive stringers, to expand both units; and means to raise the passive stringers by support from the active stringers after the units have collapsed.
